ADDRESSING AND LISTING MACHINE

Paul M. Rainey, Martinsville, N. J., assignor to
 Combination Selector Company, Glen Ridge,
 N. J., a corporation of New Jersey

Application September 14, 1937, Serial No. 163,737

20 Claims. (Cl. 101—58)

This invention relates to new and useful improvements in addressing and listing machines and systems of the type adapted to select from a large number of record members such as address plates those having certain desired identifications.

The objects of this invention are to provide an addressing or listing machine having a selector capable of making complex selections of great variety; to provide means for identifying on the envelopes or sheets on which the addressing or listing is done the class or group to which the individual plate or stencil belongs; and to simplify the mechanism so as to minimize the possibility of erroneous operation.

This invention utilizes the matrix principle of selection and control disclosed in my patents, Reissue No. 17,250 of April 2, 1929 and No. 1,863,353 of June 14, 1932. A plurality of matrices are used jointly to control the selection of a record member, and this makes possible selections which could not be effected with the single matrix selector as disclosed in Reissue Patent No. 17,250 or with the multiple matrix selector disclosed in Patent No. 1,995,595 of March 26, 1935, issued to Arthur H. Adams and myself, or with the one disclosed in my copending application Serial No. 18,483, filed April 26, 1935.

It is well known in the art that the total number of different identifications on an individual address plate, stencil or record member is the number of different indications per selecting position raised to a power equal to the number of selecting positions. Hence, on a 24 selecting position plate or stencil using two indications (tab or no tab, hole or no hole, notch or no notch, etc.) per selecting position, there are 2^{24} different identifications possible. Likewise, in a 24 selecting position plate or stencil using three indications (long tab, short tab, or no tab; large hole, medium hole or small hole; deep notch, medium depth notch or no notch, etc.) per selecting position, there are 3^{24} different identifications possible.

In order to appreciate the limitations of a selector equipped with but a single matrix, let us consider a simple case involving only three selecting positions.

The number of different identifications possible for two indications per selecting position will then be 2^3 or 8 for three indications per selecting position 3^3 , or 27.

Table I below shows the eight different identifications for two indications per selecting position, and Table II shows the twenty-seven differ-

ent identifications for three indications per selecting position.

Table I

NOTE.—X indicates presence of indicia (tab, hole or notch).
 O indicates absence of indicia (tab, hole or notch).

Different identifications	Selecting positions			10
	1	2	3	
1.	X	X	X	
2.	O	X	X	
3.	X	O	X	
4.	O	O	X	
5.	X	X	O	15
6.	O	X	O	
7.	X	O	O	
8.	O	O	O	

Table II

NOTE.—a, b, c, indicate, respectively, the three indications possible per selecting position.

Different identifications	Selecting positions			25
	1	2	3	
1.	a	a	a	
2.	b	a	a	
3.	c	a	a	
4.	a	b	a	
5.	b	b	a	
6.	c	b	a	
7.	a	c	a	
8.	b	c	a	
9.	c	c	a	
10.	a	a	b	
11.	b	a	b	
12.	c	a	b	
13.	a	b	b	
14.	b	b	b	
15.	c	b	b	
16.	a	c	b	
17.	b	c	b	
18.	c	c	b	
19.	a	a	c	40
20.	b	a	c	
21.	c	a	c	
22.	a	b	c	
23.	b	b	c	
24.	c	b	c	
25.	a	c	c	
26.	b	c	c	
27.	c	c	c	45

It should be noted that Table II includes Table I. For example, if we eliminate from Table II the nineteen identifications containing b, there will remain eight identifications containing a and c, and if X is substituted for a and O for c, those eight identifications will duplicate Table I.

It will be clear from this that an addressing or listing machine equipped with a single matrix

selector adapted for use with plates having three possible indications per selecting position may also be used with address plates, stencils or record members having only two possible indications per selecting position, provided these two indications are the same as two of the three indications for which the selector is adapted.

It is well known in the art that a single matrix selector can positively select any group of plates indicated by the different identifications (first column, Tables I and II), even when these tables are extended to provide for any number of selecting positions. It is also known in the art that a single matrix selector can select certain groups of the different identifications. For example, a single matrix selector can select from Table I all plates bearing different identifications 1 and 2; 1, 2, 3 and 4; 1, 3, 5 and 7; 5, 6, 7 and 8, etc., and in Table II groups such as 1, 2 and 3; 1-9; 10-12 and 19-21; 1, 4, 7, 10, 13, 16, 19, 22 and 25, etc. On the other hand, groups like 2 and 3; 2 and 7; 3 and 5; 1, 2 and 7; 1, 2, 3 and 6; 1, 4, 6 and 7 of Table I are not selectable, and there are many groups of Table II which are likewise not selectable with a single matrix.

The device arranged in accordance with the present invention makes all of these and many other groups selectable.

A preferred embodiment of this invention is a unit one or more of which could be used with or in place of units 2, 3 or 4 of Patent No. 1,995,595, referred to above. This unit is arranged to use a plurality of matrices and may use any number. These matrices test separate patterns of pins and the compliance or non-compliance of these matrices determines selection as otherwise determined by the matrices to effect the printing from the plates desired. For example, if it is desired to print a list of all plates bearing identifications 2 and 3 of Table I and no others, two matrices will be prepared as follows: matrix 1 selects only group 2 and matrix 2 selects only group 3. The matrices are also prepared so that printing will occur if either matrix complies with its associated pattern of pins. The same result could be obtained by preparing three matrices as follows: matrix 1 to comply with identifications 1, 2, 3 and 4 of Table I, matrix 2 to comply with identifications 1 of Table I, and matrix 3 to comply with identifications 4 of Table I. The three matrices should then be so modified that printing can only occur when matrix 1 complies and when both matrices 2 and 3 fail to comply. This means that the only plates printed are those bearing identifications 2 and 3 of Table I. In other words, the determinations of the various matrices may be added to or subtracted from one another as determined by the matrices. Thus in a four matrix selector it will be possible positively to select: (1) the sum of any four groups of plates selectable by a single matrix; (2) the sum of any three groups of plates selectable by a single matrix less those plates which comply or do not comply with the fourth matrix; and (3) the sum of any two groups of plates selectable by a single matrix less those which comply with neither or with both of the other two matrices.

While the present disclosure shows the invention applied to the control of printing from address plates or stencils, as determined by indicia in the form of notches, it is understood that the invention is applicable and contemplates the control of other functions such as sorting, counting, adding, subtracting and the like, and that the indicia may be tabs, holes, embrasures,

electrically conducting or insulating materials or opaque or transparent areas or any means of effecting an indication which is capable of being sensed.

The provision of multiple matrices makes it possible to print on the envelope or list an identification of any of the matrices which complies with its pin pattern. This is a very valuable feature as the following illustration will show. Referring to Table I, let us assume that it is desired to mail a special catalogue to all those whose plates have identifications 2 and 3, and that it is desired to accompany the catalogues to group 2 with a special letter not intended for group 3. The matrix determining the selection of group 2 is, in accordance with the present invention, so modified as to cause the machine to print on the envelope an identifying symbol for every plate having identifications 2. Similarly, each separate matrix may cause the printing of an identifying symbol.

The above mentioned and further objects and advantages and the manner of obtaining them will be made clear in the following description of a preferred embodiment and from the accompanying drawings, in which

Fig. 1 shows a plan view of the front or working end of one unit with printing platen removed to show address plate in selecting and printing position;

Fig. 2 shows a front elevation of unit with front cover removed;

Fig. 3 shows a side section substantially on the line A—A of Fig. 1;

Fig. 4 shows a time chart of certain functions of the machine;

Fig. 5 shows a partial side section on the line B—B of Fig. 1;

Fig. 6 shows a detail of certain parts of Fig. 2;

Fig. 7 shows a portion of an address plate indicating the two kinds of notches used as indicia;

Fig. 8 shows a preferred form of matrix member;

Fig. 9 shows a plan section substantially on the line C—C of Fig. 2; and

Fig. 10 shows a plan view of an installation consisting of one feeding or stack unit, three multiple selector units of the kind described in detail herein, a matrix sorting or throw-out unit, and a terminal stacking unit.

Referring to the drawings, Fig. 1 shows address plate 1 in the printing position, 1^a shows the position of the preceding address plate, 1^b shows the position of the succeeding address plate. During one cycle of the machine the address plates are moved forward one step at a time during approximately one-half of the cycle as indicated in Fig. 4. During one cycle one plate will be moved from the position 1^b to the position of address plate 1, and the address plate in the position of plate 1 will be moved to the position of address plate 1^a, e. g., by the feeding mechanism described in Patent No. 1,995,595.

The unit is mounted either singly or with other similar units, as shown in Fig. 10, between a stack or feeding unit 2, and a matrix sorting unit 6 followed by a stacking unit 7. Fig. 10 shows three of these units so mounted and numbered 3, 4 and 5. Each of these units consists of two frame plates 8 and 9 (see Figs. 1 and 2) suitably spaced by spacers 10 (one shown in Fig. 9). Frames 8 and 9 also support address plate-feeding rack 11 and are arranged to be connected with adjoining units by bolts 12 and 13 (Fig. 9). Frames 8 and 9 are arranged to hold front cover 75

14 (Fig. 1) and the mechanism between the frames is enclosed by suitable cover plates 15, 16 and 17 (Fig. 3).

The edge of each address plate bears indicia in the form of notches as shown in Fig. 7. A shaft 18 is supported in the two frames 8 and 9 and is provided at one end with a suitable coupling arrangement 19 and at the other end a complementary coupling arrangement 20. Coupling arrangement 19 of one unit will engage the complementary coupling arrangement 20 of an adjoining unit or of the stack and feeding unit 2 (Fig. 10). Similarly, coupling arrangement 20 will connect with coupling of matrix selector unit 6 or stacking unit 7 (Fig. 10). The shaft 18 is spaced between the frames 8 and 9 by collars 21 and 22 rigidly connected to shaft 18 (Fig. 9). Shaft 18 also carries cams 23, 24, 25 and 25^a and 26, rigidly connected to shaft 18 by set screws.

Shaft 18 makes one complete revolution per cycle in the direction of the arrow (see Figs. 3 and 5), during approximately half of which time the address plates are moved forward one step. During the remaining half of the cycle the address plates remain stationary in positions 1, 1^a and 1^b. In Fig. 3 the address plate is in position 1 which is the testing position. As shaft 18 rotates in the direction of the arrow, a U-shaped bale 27 pivoted at 28 and with its two lower extremities 29 and 29^a engaging cams 25 and 25^a, respectively, is rotated in a counter-clockwise direction, thus permitting bell-cranks 30, also pivoted at 28 (of which there is one for each selecting position), to rotate in a counter-clockwise direction. Each bell-crank 30 is urged to move in a counter-clockwise direction by a selecting bar 31 which hooks over the left-hand end of the horizontal arm of bell-crank 30. Bell-crank 30 continues to rotate in a counter-clockwise direction until its vertical arm engages either the edge of address plate 1 or the bottom of a notch in the address plate. Each selecting bar 31 carries a plurality of pins, only two of which are shown at 32 and 32^c (Fig. 3). The selecting bars are free to move vertically in slots in members 33 and 33' (Fig. 9) mounted between members 34 and 34^a provided with brackets 35 which are attached to lugs 36 of frames 8 and 9. The selecting bars 31 are maintained in their slots by cover plates 37 and 37'. Opposite each set of selecting bar pins 32, 32^c, etc. (a, b and c), is mounted a matrix holder 38, each adapted to hold a matrix like 39 (Fig. 8). As bell-cranks 30 come to rest in their counter-clockwise movement, all selecting pins whose bell-cranks 30 are arrested by the edge of an address plate, will come to rest opposite the upper row of hole positions of matrix 39. All pins 32 whose corresponding bell-cranks 30 come to rest in the bottom of a shallow notch 40 (Fig. 7) will come to rest opposite the middle row of hole positions of matrix 39. All the selecting bar pins 32 whose corresponding bell-cranks come to rest with the vertical arms in the bottom of deep notches 41 (Fig. 7) will be positioned opposite the lower row of hole positions in matrix 39. In this way the selecting bar pins 32 form patterns of the indicia cut in the edge of the address plate under test.

Selection is determined by the conformity or non-conformity of these patterns of pins with prepared matrices 39 inserted in the various matrix holders 38 in a manner similar to that described in my Reissue Patent No. 17,250. Matrix 39 provides for certain controls in addition to the determination of selections by holes in the

three positions corresponding to each selecting bar 31. These are indicated by positions for punching elongated holes at positions marked "and", "or" and "D. C."

Matrix holders 38 (a, b and c) are pivoted at 40 to members 34 and 34^a. On the same pivot on 34 is a member 41, the lower end of which carries a projection 42 which is bent in a horizontal direction. The edge of this member toward the matrix holder 38 carries an angular projection 43 which will engage with the "and" position of matrix 39 unless this section is cut away. If the "and" position of the matrix is not cut away, projection 42 will be in the position shown in Fig. 3 by dotted line at 44. If the "and" position of matrix 39 is cut away, the angular projection 43 will pass through the matrix and assume the position shown by solid lines at 42. This movement is assured by a spring between the upper lug of 41 and a corresponding lug on a horizontal arm 45 of matrix holder 38. All the matrix holders are equipped with members like 41 which operate in a similar manner.

As cam shaft 18 continues to rotate in the direction of the arrow, one end of lever 46 pivoted at 47 to bracket 48 attached to member 34, is caused to rotate in a clockwise direction by pin 49 in member 50, urged upward by spring 51 (see Fig. 6) on mounting studs 52 rigidly mounted on member 34. On member 50 below each matrix holder 38 is a projection 53 (Fig. 3), on the upper side of which is a notch 54. As member 50 moves upward under the tension of spring 51 as controlled by cam 24, pins 55 permit the matrix holders 38 to rotate in a counter-clockwise direction under tension of springs 72 (see Fig. 5). The position of projections 42 of members 41 will be determined by whether or not the respective matrices have the "and" portion cut away and whether the pattern of pins 32 all find holes in the matrices. Each projection 42 will come to rest either at the left of the associated notch 54, over the notch or to the right of the notch. Member 50 cannot continue to rise, therefore, unless all of the projections 42 are positioned over notches 54. If member 50 is permitted to rise to the extent permitted by cam 24 by all the members 42 engaging notches 54, this movement will impart through link 56 a movement to member 57. This member is pivoted at 58 and 59 to plates 60 and 61 mounted on members 33 and 33', respectively. The member 57 will rotate in a horizontal plane so that its upper projection 62 will be moved from under pin 63, thus enabling print lever 64 to rotate in a clockwise direction about its pivot 91 when cam 23 has rotated sufficiently far for projection 65 of print lever 64 to engage the cutaway portion of cam 23. This movement is effected by spring 66, one end of which is attached to pin 63 rigidly mounted to print lever 64 and the other end to a pin 67 mounted in frame 8 (Fig. 2). The clockwise rotation of print lever 64 about its pivot 91 causes printing platen 67 attached thereto to move downward and press any paper or envelope that may have been placed under it against ink ribbon 68 and address plate 1, causing an impression to be made on the paper or envelope. The ink ribbon 68 is moved longitudinally a small increment for each movement of print lever 64 by a mechanism not shown but well known in the typewriter and other arts.

Thus it will be clear that the rotation of member 57 upon its pivots 58 and 59 will determine the printing of any address plate which may occur 75

cup the position of address plate 1 (Fig. 1). This rotation is effected by member 50 being permitted to rise by the location of projections 42 over notches 54. The position of projections 42 over their respective notches 54 is determined by a matrix which complies with the pin pattern and has its "and" section cut away, or by non-compliance with the pin pattern provided the "and" section of matrix 39 is not cut away.

10 Members 69 having triangular projections 70 and horizontal projections 71 (Figs. 2 and 3) are pivoted at 40. The position of the members 69 when the "or" portion of the matrix is not cut away is shown by the dotted lines of 71^c, and the 15 position of each of these members when the "or" portion of matrix 39 is cut away is shown by solid lines 71^c in Fig. 3. The projections 71 project toward member 57 and will cause its rotation upon its pivots 58 and 59 whenever the "or" portion 20 of the corresponding matrix is not cut away and when the matrix complies with the pattern of pins. The rotation of member 57 by 71 is independent of the rotation produced by the upward movement of member 50 as previously described.

25 Hence, by using matrices with the "or" section not cut away, printing will be caused by any matrix complying with the pin pattern.

The continued rotation of shaft 18 causes cam 24 to lift the right-hand end of lever 46, pressing down pin 49 of member 50 and pins 55 and 30 rotating matrix holders 38 in a clockwise direction against the tension of springs 72 (Fig. 5) out of engagement with pins 32. Cams 25 and 25^a will thus rotate bale member 21 on its pivot 28 by 35 engaging projections 29 and 29^a, and will restore the bell-cranks 30 and their associated selecting bars 31 to the position shown in Fig. 3. Cam 23 will restore printing arm 64 by surface 73 engaging the projection 65, thus completing one 40 cycle of operation.

PRINTING ADDRESS PLATE IDENTIFICATIONS

The feature of printing an identification of address plates complying with matrices and thus denoting classification will now be described.

On the right-hand pivots of matrix holders 38 (Fig. 2) are members 74 (best shown in Fig. 5). Each of these members carries a triangular projection 75 which engages the "D. C." portion of the matrix unless this portion is cut away. In Fig. 5, 74 shows the position of these members when the portion, "D. C." is cut away, and 74 shows the position when the "D. C." portion is 55 not cut away. Each member 74 has a projecting arm 76 which engages surfaces 77 of members 78 pivoted at 79 in bracket 80 attached to feeding channel 11. Each member 78 is slotted as shown at 81 and is urged to rotate in a clockwise direction by springs 82. The upper ends of the members 78 engage members 83 which bear identifying symbols in the form of type for the figures 1, 2, 3 and 4, respectively. Slotted member 84 is free to move on pin 85 mounted in bracket 80 and on 60 shoulder screw 86 in bracket 87 attached to 43^a and urged downward by spring 88, one end of which is attached to 84 and the other end to 87. Member 84 carries a cam wiper 89 which engages cam 26. This cam is so designed as to maintain 65 member 84 in its upper position during the printing time as shown in Fig. 4. In this position members 83 will be lifted so that the type indications on members 83 are in the same plane with the type surfaces of the address plate in position 70 1, providing members 78 have been rotated in a

counter-clockwise direction around pivot 78, so that their lower extremities extend into the path of ears 90 of member 84. In making this movement slots 81 of members 78 provide the necessary freedom of motion. The operation just described is completed within the same cycle as the other functions of the machine.

Matrix 39 may be of suitable cardboard or metal and should definitely provide means for identifying the selection desired, as shown by 10 the number 146 inserted after "Sel. No.". Likewise, provision should be made to indicate the number of matrices required to effect such selection. This is indicated by the numeral 2 inserted after "No. of Mxs." Further provision should be made for indicating which matrix of the series this matrix may be. This is indicated by the number 1 after "No. this Mx.". This makes it possible for an operator to be certain that all necessary matrices are available to insure a certain selection. At the left of the upper row of selecting hole positions numbered 1-23 is a dash which may be taken to represent the edge of an address plate, and indicates the position of the feelers as determined by the edge 20 of a plate. The second row of holes (or locations for holes) has at the left an indication representing a small notch, and these holes (or locations) represent the positions of feelers determined by the presence of a shallow notch in any 25 selecting position. Likewise, the lower row of holes (or locations for holes) has an indication for a large or deeper notch, and these holes (or locations) represent the positions of feelers when located by deep notches in the edge of any address plate in any of the varying selecting positions. These indications on a matrix are of assistance to operators in the preparation of matrices, particularly until such time as they become thoroughly familiar with the working of 30 the selector.

EXAMPLE OF OPERATION

The following are a few examples to illustrate 45 the utility and flexibility of this selector. First we will assume a simple (two indications per selecting position) classification using notch indicia. We will use only the shallow notches, which means that no pattern of pins will ever contain pins opposite the lower row of hole positions of the matrix. It will then not be necessary to punch any holes in the lower row of hole positions on any matrix.

In the following classification of a file of customers' names and addresses, the interpretation 55 of indicia (notches and no notches) is as follows: "X" indicating a notch and "O" indicating no notch:

Classification		
Selecting position	Indicia	Interpretation
1-----	X	Retailer (R).
1-----	O	Not a retailer (not R).
2-----	X	Wholesaler (W).
2-----	O	Not a wholesaler (not W).
3-----	X	Manufacturer (M).
3-----	O	Not a manufacturer (not M).

Example 1.—Suppose it is desired to address envelopes or make a list of all the names and addresses of customers who are manufacturers and retailers or manufacturers and wholesalers. Referring to Table I, it will be noted that it is desired to select and print all plates bearing 70 75

identifications 1, 2 and 3. Matrices to effect this selection are as follows:

Matrix 1

Selecting positions

"and"	"or"	(All other)	3	2	1	D.C.
X	X		O	X	X	X
X			X	X	X	
O			O	O	O	

Matrix 2

Selecting positions

"and"	"or"	(All other)	3	2	1	D.C.
O	X		X	X	X	X
X			X	O	X	
X			X	O	O	

Note.—"X" above indicates portions of matrix which are cut away or punched out and "O" indicates that they have not been removed.

The two matrices prepared as indicated above may be inserted in any two of the four matrix holders 38. Matrix holders with no matrices will not affect selection, since the movement of these holders cannot be limited by the pins; likewise no members 71 associated with these vacant holders will cause printing, since there is no matrix to hold such member in the position shown by dotted lines for 71^c of Fig. 3, and since the projection 42, 42^a, 42^b or 42^c will be located over its corresponding notch 54, 54^a, 54^b or 54^c.

The first matrix (matrix 1 above) will comply with the pin patterns of all, and only those address plates having a notch in position 3 indicating "manufacturer" or groups 1, 2, 3 and 4 of Table I. If the first matrix is inserted in the first matrix holder 38, then each time the pattern of pins 32 complies with the matrix, the projection 42 will be located directly above notch 54 as shown by dotted lines at 44 (Fig. 4), since the "and" position of matrix 1 is cut away. The second matrix (matrix 2 above) (in matrix holder 38^c) will comply only with the pattern of pins established by plates belonging to group 4 of Table I having a notch in selecting position 3 and no notches in positions 1 or 2. In the position of non-compliance, the projection 42^c will be located directly over notch 54^c because the "and" position of the second matrix was not punched out, thus permitting the member 50 to rise sufficiently to rotate 57 on its pivots 58 and 59. This will move projection 62 from under pin 63 and printing will take place from the desired plates. However, in the compliance position, projection 42^c will be moved to position shown in dotted lines 44^c (Fig. 4) to the right of notch 54^c, thus preventing member 50 from rising to effect the rotation of member 57 on pivots 58 and 59, and causing printing by moving projection 62 from under pin 63. The selection effected is therefore groups 1, 2, 3 and 4, less group 4 or groups 1, 2 and 3. This is an example of subtraction of groups effected by the cooperation of two matrices. Matrices once prepared and used may be filed away for future use, thus eliminating the possibility of human error in the preparation of new matrices or in the setting of pins of the proper length in proper holes or the setting up of proper electrical circuits as is required by certain commercial selectors.

Example 2.—Let us assume that it is desired to make a list of the names and addresses of all customers including those who are retailers and wholesalers, and those who are wholesalers and manufacturers, but excluding those who are retailers and wholesalers and manufacturers. Table I indicates that all plates should be printed bearing identifications 2 and 5, and plates bear-

ing identification 1 must not be printed. The matrices for this selection are as follows:

Matrix 1

Selecting positions

"and"	"or"	(All other)	3	2	1	D.C.
O	O		O	O	X	X
X			X	X	X	
O			O	O	O	

Matrix 2

Selecting positions

"and"	"or"	(All other)	3	2	1	D.C.
O	O		X	X	O	X
X			O	O	X	
O			O	O	O	

Matrix 1 will select and cause printing from all plates bearing identification 2 of Table I and no others. Likewise, matrix 2 will select and cause printing of all plates bearing identification 5 of Table I and no others. Plates bearing identification 1 of Table I will not comply with either matrix and therefore will not be printed. The result will therefore be the desired list. This is an example of the addition of groups by the co-operation of two matrices.

It should be noted that these matrices have no punchings in either the "and" or the "or" position. The "or" position is not punched because it is desired to have each matrix initiate printing independently by means of the member 71 associated with the particular matrix holder 38. As previously explained, members 71 cannot initiate printing unless positioned by a matrix (not cut away in the "or" position) engaging the corresponding triangular projection 10. There would be no point to cut away the "and" position of the matrices because the position of projections 42 is of no consequence when the printing is determined by one or more of the members 71.

Example 3.—Suppose it is desired to address envelopes to all retailers regardless of their status as wholesalers or manufacturers. This will include groups 1, 3, 5 and 7, Table I. Suppose also that it is desired to identify the retailers who are not wholesalers or manufacturers and (group 7, Table I) those retailers who are also wholesalers regardless of their status as manufacturers (groups 1 and 5, Table I). For this three matrices will be required as follows:

Matrix 1

Selecting positions

"and"	"or"	(All others)	3	2	1	D.C.
O	O		X	X	O	X
X			X	X	X	
O			O	O	O	

Matrix 2

Selecting positions

"and"	"or"	(All others)	3	2	1	D.C.
O	O		X	X	O	O
X			O	O	X	
O			O	O	O	

Matrix 3

Selecting positions

"and"	"or"	(All others)	3	2	1	D.C.
O	O		X	X	O	O
X			X	X	X	
O			O	O	O	

In the previous examples it has been pointed out that the matrices may be placed in any of the matrix holders indiscriminately. In the present case there is an operating advantage of placing the matrices in the holders whose corresponding identification number (type on members 83) corresponds to the matrix number. This facilitates checking the identification. Let us therefore consider that the above matrices have been placed as follows:

Matrix 1 in matrix holder 38^c, whose corresponding identification number (on the associated member 83) is 1;

Matrix 2 in matrix holder 38^b, whose identification number is 2;

Matrix 3 in matrix holder 38^a, whose identification is 3.

5 Matrix 1 will comply with the pattern of pins set up by all plates with a notch in position 1, regardless of other notches, and since it is not punched in the "or" position it will cause the printing from all plates of customers who are 10 retailers, regardless of their status as wholesalers or manufacturers. This will include groups 1, 3, 4 and 7 of Table I. Further, since the D. C. position is punched, this matrix will cause no identification to be printed above and in front of 15 the addresses printed.

Matrix 2 will comply only with plates having a notch in position 1 and no notches in positions 2 and 3. It is not punched in the D. C. position and since it has been placed in the matrix holder

20 38^b, will cause the printing of the number 2 above and in front of the address of each retailer who is not a wholesaler and not a manufacturer. Thus all envelopes addressed by plates in group 7 will be identified by the figure 2 printed above 25 and in front of the address.

Matrix 3 in matrix holder 38^a and, not punched in the D. C. position, will cause the identification of all plates of customers who are retailers and wholesalers, regardless of their status as manufacturers, groups 1 and 5 of Table I, by printing a 30 3 above and in front of these addresses.

It should be noted that matrices 2 and 3 are not punched in the "or" position. Punching in this position would not alter the selection just 35 described, since the selection of matrix 1 includes the selection of matrices 2 and 3. By not punching this position, these matrices 2 and 3 are available to cause the printing of their respective selections if such list is required at any time. All 40 other positions in the two upper rows of the above matrices have been shown as punched so that they are available to make their respective selections regardless of the indicia in these other positions.

45 Similarly, it is possible to effect selections involving the addition and subtraction of groups using the three indications per selecting position as shown in Table II.

What I claim is:

50 1. In a record-selecting system, record members having indicia, a plurality of matrix members, each adaptable to conform with any combination of indicia that may be found on a record member, and selecting means cooperating simultaneously with said plurality of matrix members to select record members possessing the combinations of indicia jointly determined by said matrix members.

60 2. In a record-selecting system, record members having indicia along their edges, a plurality of matrix members, each capable of being marked to represent said indicia and their location on the record members, and selecting means cooperating simultaneously with said plurality of matrix members to select those record members possessing the combinations of indicia and located in positions jointly determined by all said matrix members.

70 3. In a record selecting system, record members bearing indicia, selecting means including a plurality of matrices, means for simultaneously comparing said matrices with the indicia on said record members, and means for determining selection of record members by said comparison.

4. In a record selecting system, record members bearing indicia, means for setting up a plurality of patterns corresponding to the indicia of a record member, selecting means including a plurality of matrix members, means for comparing each matrix with a pattern, and means for determining the selection of those record members whose indicia are indicated by the matrices depending on the compliance or non-compliance of the matrices with the patterns.

5 5. In a record selecting system, record members bearing indicia, means for setting up a plurality of patterns corresponding to the indicia of a record member, selecting means including a plurality of matrix members, means for comparing each matrix with a pattern, and means for determining the selection of record members depending on the compliance or non-compliance of the matrices with the patterns.

10 6. In a record-selecting system, record plates having indicia in the form of notches of different depths cut in the edges of the plates in different positions, a plurality of matrix members, each consisting of a plate, in various portions of which small holes may be punched to correspond to the existence or non-existence of a notch of a given depth in record plates in the corresponding positions, selecting means comprising a plurality of sets of pins, one set for each matrix member, means responsive to the notch pattern on a record plate to set up a corresponding pattern in all the sets of pins, means for moving said plurality of matrix members in engagement with their corresponding sets of pins whereby the selection of any record plate will be determined by the relationship between said matrix members and their corresponding patterns determined by the notch pattern of said record plate.

15 7. In an addressing and listing machine, means for printing, record members for controlling the printing and having indicia in a plurality of locations, means for moving a member into printing position, means controlled by said member for setting up a plurality of patterns corresponding to indicia of said member, a plurality of matrices, one for each pattern set up by the last mentioned means, means for bringing into cooperative relation all of said matrices with their associated patterns, and means responsive to the relationship between said patterns and their associated 20 matrices for printing under the control of the record member in the printing position.

25 8. In a record-selecting system, record members bearing indicia, means for setting up a plurality of patterns corresponding to the indicia of a record member, record-selecting means including a plurality of matrix members having two positions, a finger for each matrix member and also having two positions, means for moving a finger into one of said two positions controlled by the associated matrix, a bar having a notch for each matrix in cooperative relation with the associated finger, and means for selecting a record member when all said fingers enter the associated notches.

30 9. In an addressing and listing machine, means for printing, record members for controlling the printing and having characteristic indicia in a plurality of locations, means for moving a member into printing position, means controlled by said member for setting up its characteristic indicia pattern in a plurality of separate sets of pins, a plurality of matrices, one for each set of pins, means for simultaneously bringing into cooperative relation all of said matrices with their 35

associated pin sets, means depending on the compliance or non-compliance of all said pin sets with their associated matrices for printing under the control of the record member in the printing position, and means controlled by one of said matrices for at the same time printing a symbol characteristic of that particular matrix.

10. In an addressing and listing machine, means for printing, record members for controlling the printing and having characteristic indicia in the form of notches of various depths in a plurality of locations along their edges, means for moving a member into printing position, means controlled by said member in the printing position for setting up sets of pins in a pattern characteristic of the depth and location of the notches, a plurality of matrices, one for each set of pins, and each arranged to be perforated to represent any desired pattern of record member indicia; means for simultaneously bringing into cooperative relation all of said matrices with their associated sets of pins, means depending on the compliance or non-compliance of all said sets of pins with their associated matrices for printing under the control of the record member in the printing position, and means controlled by one of said matrices for at the same time printing a symbol characteristic of that particular matrix.

30. 11. In an addressing and listing machine, printing means, record members for controlling the printing and having positional indicia, means for moving a member into the printing position, a plurality of pin patterns set up by the member and representing the indicia thereon, a plurality of matrices, one for each pin pattern and cooperating therewith, and means for actuating the printing means depending on the joint effect of said matrices.

40. 12. In an addressing and listing machine, record members having positional indicia of different characteristics, means controlled by said members for setting up a plurality of patterns representing the indicia on a particular record member, a plurality of matrix members, one for each pattern and cooperating therewith, means controlled by the matrices for selecting in accordance with the sum of any two groups of record members selectable by a single matrix less those which are selectable by one other matrix.

50. 13. In an addressing and listing machine, means for printing, record members for controlling the printing and having positional indicia of different characteristics, means for moving a member into printing position, means controlled by said member in the printing position for setting up four patterns of pins representing the indicia on the record member, four matrix members, one for each pin pattern and cooperating therewith, means controlled by the matrices for printing in accordance with the sum of any two groups of record members selectable for printing by a single matrix less those which are selectable for printing by two other matrices.

65. 14. In an addressing and listing machine, record members having positional indicia of different characteristics, means controlled by said members for setting up a plurality of patterns, each pattern representing the indicia on a particular record member, a plurality of matrix members, one for each pattern and cooperating therewith, and means controlled by the matrices for selecting record members in accordance with the sum of any of a plurality of groups of record members selectable by a single matrix member.

15. In an addressing and listing machine, means for printing, record members for controlling the printing and having positional indicia of different characteristics, means for moving a member into printing position, means controlled by said member in the printing position for setting up four patterns of pins representing the indicia on the record member, four matrix members, one for each pin pattern and cooperating therewith, means controlled by the matrices for printing in accordance with the sum of any four groups of record members selectable for printing by a single matrix member.

10. 16. In an addressing and listing machine, record members having positional indicia of different characteristics, means controlled by said members for setting up a plurality of patterns, each pattern representing the indicia on a particular record member, a plurality of matrix members, one for each pattern and cooperating therewith, means controlled by the matrices for selecting record members in accordance with the sum of any three groups of record members selectable by a single matrix member less those record members the selection of which is determined by another matrix member.

15. 17. In an addressing and listing machine, means for printing, record members for controlling the printing and having positional indicia of different characteristics, means for moving a member into printing position, means controlled by said member in the printing position for setting up four patterns of pins representing the indicia on the record member, four matrix members, one for each pin pattern and cooperating therewith, means controlled by the matrices for printing in accordance with the sum of any three groups of record members selectable for printing by a single matrix less those record members the selection of which for printing is determined by the fourth matrix member.

20. 18. In a record-selecting system, record members having characteristic positional indicia, a plurality of matrix members, each adjustable in accordance with any combination of indicia that may be found on a record member by perforating it in accordance with the location and characteristics of the indicia, and selecting means cooperating simultaneously with said plurality of matrix members to select record members possessing the combinations of indicia jointly determined by said matrix members, said selecting means comprising a plurality of arms, one for each indicium position, said arms being variably movable in accordance with the location and character of the indicia, a plurality of selecting bars, one for each arm and variably displaced thereby depending on the extent to which the arm has been moved, and a plurality of pins carried by each bar, one for each matrix and cooperating with the holes therein.

25. 19. In a record-selecting system, record members having characteristic indicia in the form of notches of varying depths along the edges of said record members, a plurality of matrix members, each adjustable in accordance with any combination of indicia that may be found on a record member by perforating it in accordance with the location and depth of the notches in said record members, and selecting means cooperating simultaneously with said plurality of matrix members to select record members possessing the combinations of indicia jointly determined by said matrix members, said selecting means comprising a plurality of pivoted arms, one for each indicium

position, engaging the indicia-bearing edge of the record member and urged to drop within the notches, a plurality of selecting bars, one for each arm and variably displaced thereby depending on the extent to which the arms drop within said notches, and a plurality of pins carried by each bar, one for each matrix and cooperating with the holes therein.

20. In a record-selecting and printing system, record members carrying information to be printed and having characteristic indicia in the form of notches of varying depths along the edges of said record members, a plurality of matrix members, each adjustable in accordance with any combination of indicia that may be found on a record member by perforating it in accordance with the location and depth of the

notches in said record members, and selecting means cooperating simultaneously with said plurality of matrix members to select record members possessing the combinations of indicia jointly determined by said matrix members, said selecting means comprising a plurality of pivoted arms, one for each indicium position, engaging the indicia-bearing edge of the record member and urged to drop within the notches, a plurality of selecting bars, one for each arm and variably displaced thereby depending on the extent to which the arms drop within said notches, a plurality of pins carried by each bar, one for each matrix and cooperating with the holes therein, and means for printing from a record member 15 jointly controlled by said bars and matrices.

PAUL M. RAINES.
